FLUSH BOX COVER

Frank P. Scully, Jr., New York, N.Y., assignor to Scully Signal Company, Melrose, Mass., a corporation of Massachusetts

Filed Nov. 19, 1959, Ser. No. 854,070

1 Claim. (Cl. 220—3.8)

This invention relates to the fuel oil industry. In certain cities, particularly Philadelphia, it has been customary to position the outer ends of the fill pipe and vent pipe of a fuel oil tank in a device known in the trade as a flush box. This box is generally positioned in the foundation wall of the building with its outer side substantially flush with the outer side of the foundation. Heretofore the flush box face has been covered with a plate which concealed the outer ends of the fill pipe and vent pipe. The screw plug closing the end of the fill pipe was within the confines of the sides of the box and was concealed by the covering plate which was customarily affixed to the box by suitable screws. which system has necessitated certain piping additions at the box. These additions, however, normally extend beyond the face of the box, making it impossible to continue the use of the conventional cover plate.

Accordingly, the present invention is directed toward the provision of a new and novel type of cover plate which cooperates with and effectively covers the front of the box, protecting the end of the vent pipe while allowing certain elements of the modified filling system to project through an opening in the cover plate. The cover plate instead of being screwed to the face of the box as in the prior practice is maintained in cooperative position against the box by the coaction of securing means on the cover plate which are removably affixed to the piping that protrudes through the plate from the face of the box.

The invention will be more particularly understood as the description proceeds with the aid of the accompanying drawings in which

FIG. 1 shows the general arrangement of a fuel tank in the basement of a building with the connecting fill and vent pipes terminating in a flush box located in the building wall.

FIG. 2 is an enlarged side elevation of the complete assembly showing the extension of the fill pipe and the closure cap affixed thereto.

In recent years, an improved system for connecting the fuel truck hose to the fill pipe has been developed.

FIG. 3 is a vertical section taken on the line 3—3 of FIG. 2 showing the cover plate in elevation and the means for attaching the plate to the fill pipe extension.

FIG. 4 is a front elevation of a modified form of cover plate adapted to be used on a box in which the vent pipe and fill pipe are side-by-side rather than one over the other.

FIG. 5 is a side elevation of the cover plate shown in FIG. 4.

Referring first to FIG. 1, there is illustrated one form of conventional arrangement found in buildings that use fuel oil. A tank 2 positioned on the cellar floor 4 has a fill pipe 6 through which fuel oil is fed to the tank and a vent pipe 8 through which the displaced gas is discharged from the tank. The fill pipe 6 and the vent pipe 8 are shown in FIG. 1 connected to a flush box generally referred to at 10 with the fill pipe being connected to a lower tubular neck 12 and the vent pipe connected to an upper tubular neck 14. It is customary for the fill pipe to be screwed into the neck 12 to make a liquid tight connection, but the end of vent pipe 8 may be merely slid into the extension 10.

As illustrated more clearly in FIGS. 2 and 3 the flush

2

box comprises a rectangular front element 16 which lies substantially flush with the wall 18 in which the box is positioned. The tubular neck 12 is threaded as at 20 to engage corresponding threads 22 on the end of fill pipe 6. The upper extension 14 has a circular opening 24 therethrough into which the end 26 of vent pipe 8 may be received.

The outer end of the passage 28 through the neck 12 terminates in a short upwardly directed elbow 29 which is threaded as at 30. According to the prior practice, the threads 30 would receive a correspondingly threaded plug which would effectively close the outer end of the fill pipe when the device was not in use. Now, however, in order to speed up the delivery of fuel oil, it is customary to position in the threads 30 a short nipple 32 on the outer end of which is screwed a device known as an adaptor 34. The outer end of this adaptor has a single coarse thread to which may be applied a closure cap 36. Because of the length of the nipple 32 and adaptor 34, the closure cap necessarily extends an appreciable distance beyond the face of the wall 18 and therefore cannot be covered by a face plate in the same manner in which the plug formerly applied to the threads 30 was covered.

Accordingly, I have designed a cover plate for the flush box of new and novel characteristics which may be affixed in place by attachment not to the flush box but to one of the extended piping elements. These elements may be either the nipple 32 or the adaptor 34, depending upon the exact length of these parts in relation to the cover plate securing means.

As can be plainly seen in FIGS. 2 and 3, the cover plate comprises a rectangular element 38 which has across its upper portion a plurality of louvers comprising transversely extending ports 39 with sloping, outwardly extending, hoods 40. These hoods are closed at their ends as at 41 to give maximum protection against the entry of rain or snow into the vent and fill pipes. These louvers are located immediately in front of the end of vent pipe 8 and the passage 24 through the neck 14. In this manner gas leaving the vent pipe can flow freely to the atmosphere through the louvers 40.

Below the louvers is a generally oval shaped opening 42 through the plate 38. The lateral dimension of this opening is such that the plate may be passed over the outer end of adaptor 34 when the cap 36 has been removed. On either side of opening 42 are a pair of upstanding ears 44 through each of which extends a set screw 46 having a pointed inner end 48. The configuration of opening 42 is such that it will fit quite closely about the upwardly sloping fill pipe extension 32—34 when in secured position on the face of the flush box.

When the plate 38 has been placed against the face 50 of the flush box 10, the louvers 40 will be in front of the discharge end of the vent pipe 8 and the adaptor 34 or the nipple 32 will lie between the set screws 46. The set screws 46 may be screwed tightly against opposite sides of the adaptor 34 or the nipple 32, as the case may be, and the pointed ends 48 will imbed themselves sufficiently in the adaptor or nipple to maintain the cover plate securely in place over the face of the box. By using set screws that have heads that may be driven by a screw driver to the right only, it is difficult for children or others to dislodge the cover plate from its secured position.

When the fuel oil truck man wishes to make a delivery, he removes cap 36, which is on the exterior side of the affixed cover plate, and then connects the nozzle 62 (see FIG. 1), by means that is well known in the trade, to the adaptor 34 in liquid tight relation. Filling may then proceed with oil entering the tank through hose 64, nozzle 62 and fill pipe 6. The displaced gas

will be discharged through the vent pipe 8 and the louvers 40 to the atmosphere.

A modified form of cover plate is shown in FIGS. 4 and 5. In this construction the cover plate indicated at 52 has the louvers 54 at one side and the oval opening 56 at the other side. The ears 58 and set screws 60 are similar to the ears 44 and set screws 46 already described. The cover plate 52 is applied to the flush box in the same manner as plate 38 so that the same protection is afforded to the discharge end of the vent pipe while enabling the outer end of the fill pipe to be available for use when required.

All of the dimensions of the cover plate may be varied at will to meet the dimensional conditions found in the flush box with which the plate is to be used, but in all cases there will be an opening through which the extended portion of the fill pipe may pass with the ears and set screws so located that the set screws may be brought into securing engagement with the extended portion of the fill pipe.

It is my intention to cover all changes and modifications of the example of the invention herein chosen for purposes of the disclosure which do not constitute departures from the spirit and scope of the invention.

I claim:

An improved flush box assembly comprising a rec-

tangular flush box having filling and venting passages extending through the rear wall of said box to fill and vent a fuel oil tank, a rectangular plate extending beyond the outlines of the open side of said flush box, said plate having a series of horizontal hooded louvers in the upper portion and an oval shaped hole in the bottom portion, a nipple having one end in permanent threaded engagement with the fill pipe within said flush box and extending at an inclined angle upwardly through said hole with the remaining end projecting beyond the outer surface of said plate, a pair of ears projecting outwardly from said plate located on opposite sides of said hole, a set screw threaded through each of said ears to engage said nipple and retain said plate thereon, a nozzle adapter for connection with an oil delivery hose secured to said remaining end of said nipple, and a removable closure cap engaged with said adapter.
